LOCKING DEVICE

Hymen Sternberg, Utica, N. Y.

Application December 17, 1954, Serial No. 475,991

3 Claims. (Cl. 132—120)

This invention generally relates to a locking device and more specifically provides improved and novel construction in a locking device for detachably securing two objects or members together.

An object of this invention is to provide a locking device that is simple in construction, easy to utilize, efficient in operation, positive, well adapted for its intended purposes and inexpensive to manufacture.

A further object of the present invention is to provide a locking device for detachably securing two members together including interengaging socket and projection means together with a movable member for retaining the socket and projection means in interlocked relation.

Still another important object of the invention is to provide a locking device conformable to the preceding objects wherein means for retaining two members in interlocked relation is frictionally retained in position.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a longitudinal, vertical sectional view taken substantially along the longitudinal center line of a combination comb and brush on which the locking device of the present invention may be utilized;

Figure 2 is a bottom plan view of the construction of Figure 1;

Figure 3 is a transverse, vertical sectional view taken substantially upon a plane passing along section line 3—3 of Figure 1 showing the relationship of the groove and the elongated rib positioned therein;

Figure 4 is an exploded perspective fragmentary view of the sliding latch mechanism for retaining the elongated rib in the elongated groove; and

Figure 5 is a side elevational view showing the locking device of the present invention employed for retaining a fishing reel on a fishing rod.

Referring now specifically to the drawings, it will be seen that the numeral 10 generally designates the locking device of the present invention including a brush designated generally by the numeral 12 having an elongated body 14 thereon with a longitudinal handle 16 projecting from one end thereof. A plurality of bristles 18 are positioned in the undersurface of the body 14 of the brush 12 in the usual manner and elongated longitudinal groove 20 is disposed in the undersurface of the body 14 and is disposed between adjacent bristles 18. The groove 20 is provided with the longitudinally extending socket 22 in one end wall thereof and the other end thereof is provided with an end wall 24. Positioned within the groove 20 is an elongated comb generally designated by the numeral 26 and including an elongated rib 28 together with projecting teeth 30 wherein the rib 28 is positioned in the groove 20 and provided with the longi-

2

tudinal projection 32 on one end thereof for engagement in the socket 22 in the end wall of the groove 20. The other end of the elongated rib 28 of the comb 26 is provided with a horizontally disposed notch 34 which is disposed slightly above the wall 24 of the groove 20 when the rib 28 is positioned within the groove 20.

Positioned in the bottom surface of the handle 16 of the brush 12 is a recess 36 for receiving a mounting plate 38 that is held in the recess 36 by mounting screws 40. Slidably positioned on the mounting plate 38 is an elongated latch plate 42 having depending side flanges 44 thereon and an elongated slot 46 in the center thereof together with a fastening screw 48 that is provided with a head and extends into a threaded aperture 50 in the plate 38 and into an aperture 52 in the handle 16. The screw 48 is headed and forms an abutment for the side edges of the slot 46. It will be noted that the depending side flanges 44 on the latch plate 42 increase in width from one end of the plate 42 to the other end wherein the end of the flanges 44 adjacent the notch 34 are relatively narrow and the flanges 44 adjacent the other end of the latch plate 42 remote from the notch 34 are relatively wide wherein the headed screw 48 will engage the edges of the slot 46 when the plate 42 is moved into overlying relation with a portion of groove 20 thereby frictionally locking the latch plate 42 in locked position with the end thereof in engagement with the notch 34 for locking the elongated rib 28 of the comb 26 in the groove 20. A detent 54 may be provided on the latch plate 42 for manipulating the latch plate 42 by longitudinally sliding the plate 42 into a position for latching the brush 12 and comb 26 or in a position for permitting the removal of the comb 26 from the brush 12.

As illustrated in Figure 5, the locking device of the present invention may be utilized in other orientations with one of the orientations being illustrated and including a fishing rod 56 and a fishing reel 58 having a base 60 thereon which is locked in a groove in the fishing rod 56 by the lock plate 62. The details of construction of the groove and the base 60 are the same as the details of construction of the groove 20 and the elongated rib 28. The specific locking device of the present invention may also be utilized in other various orientations and not illustrated, and the device forms a positive and readily releasable lock for easily and quickly securing one member to another member wherein the locking device may be readily unlatched for removing or detaching the members from each other.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

60 What is claimed as new is as follows:

1. A locking device for detachably securing two members together, one of said members having an elongated groove therein, said groove having at least one end wall, said end wall having a socket extending inwardly therein, an elongated longitudinal rib on the other of said members for positioning in said groove, a longitudinal projection on one end of said rib for positioning in said socket, and latch means on said one member adjacent said groove for engagement with the other member for retaining the rib in the groove and the projection in the socket thereby locking said members together, said latch means including a longitudinally slidable plate mounted

on said one member for positioning in overlying relation to a portion of the groove remote from the socket, said rib having a notch therein remote from said projection for selectively receiving said plate and securing the portion of the rib remote from the projection in the portion of the groove remote from the socket, said plate being elongated and provided with an elongated slot and depending flanges on the side edges, said flanges being longer at the end of the plate remote from the groove than at the end of the plate adjacent the groove, a headed fastening device extending through the slot for mounting the plate on said one member, said side flanges urging the edges of the slot outwardly against the headed fastener when the plate is moved longitudinally into the notch in the rib thereby frictionally locking the plate in locking position.

2. A locking device for detachably securing two members together, one of said members having an elongated groove therein, said groove having at least one end wall, said end wall having a blind socket extending longitudinally inwardly therein in inwardly spaced relation to the outer edges of the groove, an elongated longitudinal rib on the other of said members for positioning in said groove, a longitudinal projection on one end of said rib for positioning in said socket, and latch means on said one member adjacent said groove for engagement with the other member for retaining the rib in the groove and the projection in the socket thereby locking said members together.

3. A locking device for detachably securing two members together, one of said members having an elongated groove therein, said groove having at least one end wall, said end wall having a socket extending inwardly therein, an elongated longitudinal rib on the other of said members for positioning in said groove, a longitudinal projection on one end of said rib for positioning in said socket, and latch means on said one member adjacent said groove for engagement with the other member for retaining the rib in the groove and the projection in the socket thereby locking said members together, said latch means including a longitudinally slidable plate mounted on the outer surface of said one member for positioning over a portion of the groove remote from the socket, 15 said rib having a notch therein remote from said projection for selectively receiving said plate and securing the portion of the rib remote from the projection in the portion of the groove remote from the socket.
